FEEDER TO CONTAINER CAPPING
MACHINES OR THE LIKE

Manuel S. Resina, Brooklyn, N. Y.

Application July 26, 1941, Serial No. 404,160

3 Claims. (Cl. 198—34)

The present invention relates to improvements in bottle capping machines and relates more particularly to improvements in machines for automatically applying screw caps or the like to bottles and jars.

The main object in my invention is to provide an improved machine for applying screw caps to bottles or jars in an efficient manner. It includes an improved means for conveying the bottles to a cap applying position.

Other objects of my invention will be set forth in the following description and drawings which illustrate preferred embodiments thereof, it being understood that the above statement of the objects of my invention is intended generally to explain the same without limiting it in any manner.

Fig. 1 is a front elevational view of my improved machine.

Fig. 2 is a right side elevational view.

Fig. 3 is a left side elevational view.

Fig. 4 is a sectional view along line 4—4 of Figure 1.

Fig. 5 is a sectional view along line 5—5 of Figure 1.

Referring to the drawings, B designates a bench member having the vertical front and rear members 1, said front and rear members having positioned there between the motor and reduction gear mount 2.

Positioned above said mount and also held between the front and rear members 1 is the intermediate shelf 3, and positioned above the said shelf 3 on top of the front and rear members 1 is the top plate 4, said top plate 4 being reenforced by the cross pieces 5, positioned below said top plate and running from the front member 1 to the rear member 1.

Mounted on the motor mount 2 are the motor 6 and the reduction gear 7, a belt 8 joining the drive pulley 9 of the motor 6 to the pulley 10 of the reduction gear 7. The output shaft 11 leads from said reduction gear 7 and terminates at a point substantially above the top plate 4.

Keyed to shaft 11 rotatable therewith and positioned on said shaft at a point between the intermediate shelf 3 and top plate 4 is the bevel gear 12, said bevel gear 12 engages the bevel gear 13, which bevel gear 13 is fixed on a shaft 14. Situated on the shelf 3 and secured thereto by means of bolts 15, is a bushing member 16, said bushing member rotationally holding the shaft 14. Positioned on the shaft 14 at the end opposite the end holding the bevel gear 13 is a sprocket member 17.

Connected to the top plate 4 by means of a pair of bolts 18 is a conveyor holding shelf 20, said conveyor holding shelf having a vertical flange 21 connecting the upper rearwardly projecting arm 22 to the lower forwardly projecting ledge 23. Situated along the horizontal ledge 23 and running along the entire length thereof are the pair of upright channel members 24, said channel members being substantially separated and having their concave portions facing each other.

Positioned and held at each end of the channel members are the sprocket holding members and shields 26, said members 26 rotationally holding the sprockets 27 and 28, the sprocket 27 idling on axle 29, and the sprocket 28 being rotationally rigid with the shaft 30.

Keyed to the inner end of shaft 30 is a sprocket member, said sprocket member being connected to the sprocket member 17, by means of the sprocket chain 32.

The conveyor belt consists of a sprocket chain 34 engaged by the sprockets 27 and 28, said sprocket chain 34 having fixed along its entire outer perimeter the series of segmental plates 35, said plates 35 forming the continuous outer surface of the conveyor belt.

The L shaped brackets 36 having their vertical legs connected to the front face of the front vertical member 1 by means of bolts 37, have positioned on their horizontal legs the conveyor supporting ledge 39, which conveyor supporting ledge prevents the conveyor from oversagging.

A set of parallel front guide members 40 are secured to the guide holding members 41, which guide holding members are adjustably mounted by means of bolts 42 to brackets 43, which brackets 43 are secured to the outer channel member 24. A pair of rear guide members 45 similar to the front guide members 40 and parallel thereto are positioned on the opposite side of the conveyor.

Positioned on the top plate 4 are the bottle clamping and the bottle flow regulating means. Secured to top plate 4 by means of bolts 140 is the guide member 141, said guide member slidably engaging the slideable member 142 and said guide member having a longitudinal opening in its left side wall. Laterally projecting from the front end of the member 142 is the horizontal flange 143, said horizontal flange having rotatably pinned to its outer end by means of bolt 144 the lever 145, said lever having a horizontally projecting portion 147 at its front end. A T shaped bottle intercepting member 150 is removably secured to the horizontal

portion 147 by means of a pin 148, and a bolt 149 passing through the cross bar of said member into the horizontal portion 147, the intercepting arm 150 projecting forwardly of said cross bar. Projecting from and to the right of lever 145 at point anterior to the bolt 144 is the stop member 151, said stop member 151 normally passing through the longitudinal slit formed in the guide member 141, and being in contact with the side wall of member 142. Pivotally mounted on the vertical pin 152 is the pawl type catch member 153, said member having the hook shaped rear portion 154 and the forward portion 156, the counter-clockwise rotation of said pawl member being limited by pin 157 vertically projecting from lever 145 adjacent the forward portion 156.

The bottle flow regulating means above described is activated by the reciprocating arm 160, said reciprocating arm being horizontally pivotally mounted on vertical pin 161, said pin 161 being positioned on the plate 4. Vertically extending above the free end of arm 160 is the projection 164, said projection being of horizontal triangular cross-section and being adapted to engage the hooked end 154 of member 153. The vertical roller 163 mounted on the arm 160 at point intermediate the ends of said arm engages the circumferential edge of the cam 164a, which cam is rotationally rigid with the shaft 11. Tension spring 165 secured between the rear end of arm 142 and the peg 166 projecting above plate 4 impels said arm to its forwardmost position; tension spring 168 whose ends are secured to the arm 160 and the stationary peg 169 maintains said arm end at its forwardmost counter-clockwise position; tension spring 172, whose ends are secured to peg 171 projecting from the catch member 153 and to peg 170 projecting from lever 145 causes said catch member to rotate to its most counter-clockwise position; and tension spring 173 positioned between the lever 145 at a point posterior to pin 144, and a point on member 142 causes said lever to assume its most clockwise position.

The operation of my machine is as follows:

The power is turned on thus starting up the motor, the drive shaft 11, and the container conveyor. Rotating with the shaft 11 is the cam 164a, which cam in turn causes the continuous oscillation of the arm 160, which arm has the upright projection 164, said projection 164 normally passing too far to the left of the catch member 154 to engage the same. Upon placing a plurality of bottles upon the conveyor, the foremost bottle presses against the arm 150, which arm and the connected mechanism is normally kept forward by the tension spring 165. The aforementioned pressure causes the lever 145 to rotate counter-clockwise against the action of the spring 173, thus bringing the catch into the path of the oscillating projection 164 causing the catch member to engage the member 154 thus resulting in the drawing of arm 150 from the path of the bottles and allowing one to pass. When arm 160 is at its most counter-clockwise position, member 164 is anterior to the catch member 154 and is disengaged by the same, thus necessitating the pressure of another bottle to keep lever 145 in that position where the catch member may again be engaged since said lever rotates back to the position whereby member 164 is again to the left of the catch member 154. The cams 71 and 164a are so shaped and positioned that when the arm 160 is in its most clockwise position thus having 75

drawn the arm 150 out of the path of the bottles, the clamp 55 is in bottle engaging position. Hence, when a bottle is permitted to pass by the retraction of arm 150, the bottle is stopped by the left side of the clamp 55. The clamp is thence retracted, the bottle held thereby released and carried along by the conveyor, the following bottle conveyed into position and the clamp is then caused to engage the same, the speed of the conveyor being such as to carry a bottle a bottle width's distance while the clamp is in retracted position.

I have shown preferred embodiments of my invention but it is obvious that numerous omissions and alterations may be made without departing from its spirit.

I claim:

1. A means for regulating the flow of articles on a continuously moving conveyor comprising a slideably mounted member, an arm swingably positioned on said slideable member, said arm having articulately mounted and independently movable catch means mounted thereon and having its front end normally in the path of the moving articles, periodically reciprocating means adapted to engage said catch means when said catch means are in the path of said reciprocating means, said catch means being brought into the path of said reciprocating means by the pressure of the moving article against the front end of the swingably mounted arm.

2. In a machine of the character described, a continuously moving conveyor adapted to carry containers, a slideable member movable in a direction transverse to the movement of said conveyor; a rotatable arm positioned on said slideable member, said arm being pivoted about a point intermediate the ends thereof, the slideable member being resiliently maintained in forwardmost position, the rotatable arm having articulately mounted and independently movable catch means positioned on its posterior end and having its front end in the path of the moving containers when the slideable member is in its forwardmost position, periodically moving means adapted to engage the catch means when said catch means are in the path of said periodically moving means, said catch means being resiliently maintained out of the path of said periodically moving means and being brought into said path by the pressure of a moving container against the front end of the rotatable arm.

3. In a machine of the character described, a continuously moving conveyor adapted to carry containers, a slideable member movable in a direction transverse to the movement of said conveyor; a rotatable arm positioned on said slideable member, said arm being pivoted about a point intermediate the ends thereof, the slideable member being resiliently maintained in forwardmost position, the rotatable arm having articulately mounted and independently movable catch means positioned on its posterior end and having its front end in the path of the moving containers when the slideable member is in its forwardmost position, periodically moving means having a vertically disposed pin substantially triangular in cross section adapted to engage the catch means when said catch means are in the path of said periodically moving means, said catch means being resiliently maintained out of the path of said periodically moving means and being brought into said path by the pressure of a moving container against the front end of the rotatable arm.

MANUEL S. RESINA.
